UNITED STATES PATENT OFFICE.

WILLIAM WHITE, OF NEW YORK, N. Y., ASSSIGNOR TO CLARENCE WHITMAN & CO., OF SAME PLACE.

DESIGN FOR A BEDSPREAD.

SPECIFICATION forming part of Design No. 24,294, dated May 7, 1895.

Application filed April 9, 1895, Serial No. 545,109. Term of patent 3½ years.

To all whom it may concern:

Be it known that I, WILLIAM WHITE, a citizen of the United States, residing in the city, county, and State of New York, have invented 5 and produced a new and original Design for a Bedspread, of which the following is a specification.

The leading feature of my design consists in a bedspread of essentially the configuration and representation herein described and shown in the accompanying drawing, forming 10 part hereof, which drawing exhibits a quarter section of my design, it being understood that the remaining sections of the spread present 15 an appearance similar to the section illustrated.

In the drawing, A is a rosette composed of conventionalized leaves a a a edged by bands a' a'. Adjacent to the rosette are bands b b', the space between the bands being occupied 20 by interlocked rings c c. The outer band b' is bordered by a border consisting of interlocked zig-zag bands d d. Outside of the band last described are bands e e' running laterally and longitudinally of the spread, and adjacent 25 to these bands are scrolls g g h h.

The entire spread is bordered by a barred border consisting of angular bands j j. The spaces between the various bands, leaves and scrolls are filled in with a suitable filling k l. 30

What I claim is—

The design for a bed-spread, substantially as herein shown and described.

WILLIAM WHITE.
